BEATER BLADE ASSEMBLY

Aaron H. Smith, Ipswich, Mass., assignor to Signal Manufacturing Co., Lynn, Mass., a corporation of Massachusetts

Application June 26, 1956, Serial No. 593,892

7 Claims. (Cl. 259—131)

This invention relates to household beaters for use in preparing food and has for its principal objects to provide a beater assembly with improved beater action in which the diameters of the beater blade loops are not limited by the spacing of the beater sockets, to provide a beater assembly in which large diameter beaters may be employed without correspondingly increasing the spacing of the sockets and hence without having to employ larger castings, gears and so forth, which are expensive and could be used only for beaters of that size, to provide a beater assembly in which large size beaters and conventionally size beaters may interchangeably be used, and to provide a beater assembly in which large size beaters may be inserted and removed independently, that is, one may be inserted or removed without disturbing the other thus avoiding the awkwardness of having to insert and remove both at the same time.

As herein illustrated, the assembly comprises a frame carrying a pair of parallel shaft sockets for receiving the shafts of a pair of beaters which have intermeshing loops equal to or greater in radius than the distance between the sockets and in which each beater is adapted to be inserted or removed independently of the other without disturbing the socket spacing or the other beater. This is attained by tilting one beater with reference to the other as it is inserted or withdrawn to permit clearing the lower part of the beater being inserted with respect to the inserted beater. To this end one of the sockets contains an axially disposed bearing surface which has a relatively large cross-section at its mouth and a relatively smaller cross-section inwardly thereof, and the beater shaft adapted to be engaged therewith has an axially disposed bearing surface which has at its leading end a cross-section corresponding to the inner bearing of smaller cross-sectional area and rearwardly of its leading end a cross-section corresponding to that of the mouth of the socket. The leading end of the shaft permits the beater to be tilted outwardly from the other beater as it is thrust into the socket and is long enough so that the shaft may be pushed upwardly into the socket until the lower end of the beater clears the lowermost part of the other beater, whereupon it may be swung into parallelism therewith and further thrust into the socket to bring the bearing portions of the corresponding sections into driving engagement. The beater blade loops may have a radius which exceeds that distance between the sockets and both of the sockets and shafts are provided with bearing surfaces of different diameter so as to permit either one of the beaters to be removed or inserted independently of the other, although it is to be understood that it is necessary to have only one of the sockets and beater shafts constructed in this fashion.

The invention will now be described in greater detail with reference to the accompanying drawings wherein:

Fig. 1 is an elevation of a pair of beaters arranged within driving sockets, the driving mechanism being omitted;

2

Fig. 2 is a section taken on the line 2—2 of Fig. 1, looking down on the top of the beaters;

Fig. 3 is a section taken on the line 3—3 of Fig. 1;

Fig. 4 is an elevation to larger scale partly in section showing one of the beaters in the process of being inserted or removed from its driving socket; and

Fig. 5 is a horizontal section on the line 5—5 of Fig. 1.

Referring to the drawings, the beater assembly 10 (Fig. 1), includes a support 12 from which extends a pair of parallel spaced sockets 14 containing driven bearings, which will be described hereinafter, into which are drivably inserted a pair of beaters 16. Each beater has a beater shaft 18 for engagement with a bearing of one of the sockets and is made up of radial disposed blade loops 20, of which there are here shown two, fastened at their upper ends to a boss 22 fixed to the lower extremity of the shaft. The blade loops are disposed at right angles to each other and the lower end of one loop crosses the other loop and is fixed thereto by suitable means, for example a rivet 24. The blade loops, as will be seen particularly with reference to Fig. 2, have a radius r which is substantially equal to the distance between the axes of the sockets 14. In order to have beaters of this size or of a larger size, as is within the contemplation of this invention, it is necessary to omit prolongation of the shaft 18 from the boss 22, downwardly through the loops to the bottom.

With blades of the size shown and larger diameter blades it is impossible to insert or remove one beater after the other has been inserted if the spacing of the bearings is equal to or not greater than the radius of the loops. The reason for this is that where the loops intersect the distance r_1 from the axis of one beater to the crotch at the intersection of the loops of the other beater is less than the radial distance r between the axes of the beaters so that the shoulder at the lower end of the loop of the beater being inserted binds against the lower part of the inserted beater. The only recourse therefore is to intermesh the two beaters and insert them simultaneously or remove them simultaneously and this is an undesirable and awkward procedure.

In accordance with this invention the beaters are not only provided with blades in which the radial length may be as great or greater than the distance between the driving sockets but also beaters which may be removed or inserted independently of each other, that is, one may be removed without disturbing the other. This is accomplished herein by providing each beater socket with a driven bearing 26 (Fig. 4) of novel construction and the shaft of each beater with a correspondingly novel bearing for association therewith, as will subsequently appear. Conventionally each bearing has at its lower end a plurality of peripherally disposed slots 28 for interengagably receiving nubs 30 on the shafts 18. Each shaft may also have an annular shoulder 32 below the nubs 30 corresponding substantially in diameter to the lower end of the socket 14 which acts as a stop for lubricant in the bearing.

In accordance with the invention each of the bearings 26 has axially disposed internal bearing surfaces 34 and 36. The bearing surface 34 which commences at the mouth of the socket is of larger diameter than the bearing surface 36 which is located at the bottom of the socket. Each of the shafts has an axially disposed bearing of two diameters 38 and 40, the bearing 38 being at the leading end of the shaft and corresponding in diameter to the bearing 36 and the bearing 40 being located rearwardly of the bearing 38 and corresponding in diameter to the bearing 34. Because of the difference in diameters of the bearing 34 at the entrance of the socket and the bearing 38 at the leading end of the shaft 18, it is possible to insert the beater at the right-hand side (Fig. 4) at an

angle with reference to the other beater at the left-hand side, that is, tilt it outwardly away from the beater. By making the leading end 38 of sufficient length it is possible to insert the beater upwardly into the socket until the shoulder at the lower part of any one of its loops located between a pair of loops of the other beater clears the lower part of that beater, that is, the crotch between intersecting loops, whereupon the beater may be swung inwardly into parallelism with the other beater and further thrust into the socket to engage the leading end 38 with the bearing 36 and simultaneously to engage the bearing 40 with the bearing 34. Correspondingly the beater may be removed by disengaging the bearing 38 from the bearing 36, tilting the beater outwardly at a small angle and then drawing it downwardly beyond the other beater.

The bearing portions 40 are provided with peripheral grooves in which are seated spring metal lock rings 42 for yieldably and frictionally engaging the bearing portions 34 thus to retain the beaters in place.

It is evident from the foregoing that it is possible by the construction described to employ beaters wherein the blades are equal in radius to the distance between the beater sockets or exceed this distance without having to have larger castings and a greater spacing between the sockets which would entail greater cost in manufacture. Moreover it is apparent that this construction permits use of larger diameter beaters in conventionally spaced beater sockets by substituting in the sockets bearing elements such as described thus making it possible to use the apparatus with either conventional size beaters or the large size beaters described herein.

It should be understood that the present disclosure is for the purpose of illustration only and that this invention includes all modifications and equivalents which fall within the scope of the appended claims.

I claim:

1. In a beater mechanism, a frame, a pair of fixed bearing sockets mounted on the frame for receiving the shafts of a pair of beaters, with the axes in spaced parallel relation, and a pair of beaters having shafts drivably engaged with said sockets, said beaters having intermeshing blade loops, the radii of which are not less than the distance between the center lines of the sockets, the drivably engaged portions of one of the sockets and the beater shaft engaged therewith having axially disposed stepped bearing portions of different diameter permitting axial and tilting movement of the shaft within its socket to clear the beater blades of that shaft of the blades of the other beater during engagement with and disengagement from the socket.

2. In a beater mechanism, a frame, a pair of fixed bearing sockets mounted on the frame for receiving the shafts of a pair of beaters with their axes in spaced parallel relation, each beater comprising a short shaft adapted to be drivably engaged with a socket, and a plurality of blade loops disposed in planes intersecting the axis of the shaft, said loops being connected at their upper ends to the lower end of the shaft and at their lower ends to each other, said loops having diameters which are not less than twice the distance between the sockets, and means supporting the shafts in the sockets whereby one of the shafts is tiltable with reference to the other during engagement of the shaft with the socket or disengagement therefrom to permit clearing the lower end of the other beater.

3. In a beater mechanism, a frame, a pair of parallel

bearing sockets mounted thereon for receiving the shafts of a pair of beaters, said bearing sockets having a predetermined spacing, a pair of beaters having shafts adapted to be drivably engaged within said sockets, said beaters having blade loops of greater radius than the distance between the axes of the sockets, one of said sockets containing an axially disposed bearing surface which is of relatively large cross-section at the mouth and relatively smaller cross-section inwardly thereof, the one of the shafts for engagement with said socket having an axially disposed bearing surface which at its leading end corresponds in cross-section to the inner bearing of the smaller cross-sectional area and which has rearwardly of its leading end a cross-section corresponding to that of the mouth of the socket, said leading end of the shaft permitting the beater to be tilted outwardly away from the other beater as it is entered into the socket and long enough so that the shaft may be thrust upwardly into the socket until the lower end of the blade loops clears the lowermost part of the other beater, whereupon it may be swung into parallelism therewith and further thrust into the socket to bring the bearing portions of corresponding sections into driving engagement.

4. In a beater mechanism, a frame, a pair of parallel bearing sockets mounted thereon for receiving the shafts of a pair of beaters, said bearing sockets having a predetermined spacing, a pair of beaters having shafts adapted to be drivably engaged within said sockets, said beaters having blade loops of greater radius than the distance between the axes of the sockets, one of said sockets containing an axially disposed bearing surface which has a relatively large diameter at its mouth and a smaller diameter inwardly thereof, the one of the shafts for engagement with said socket having an axially disposed bearing surface which at its leading end corresponds in diameter to the inner bearing of smaller diameter and which has rearwardly of its leading end a diameter corresponding to that of the mouth of the socket, said leading end of the shaft permitting the beater to be tilted outwardly away from the other beater as it is inserted into the shaft and being long enough so that the shaft may be thrust upwardly into the socket far enough to clear the lower part of that beater with respect to the lower part of the other beater to permit it to be swung into parallelism therewith and thrust further into the socket to bring the portions of corresponding diameter into complete engagement.

5. A beater mechanism according to claim 3, wherein that portion of the beater shaft which corresponds in cross-section to the mouth of the socket carries a friction ring.

6. A beater mechanism according to claim 3, wherein that portion of the beater shaft which corresponds in cross-section to the mouth of the socket is relatively short so as to have contact only with that portion of the mouth near its entrance, and contains an annular groove and a spring friction ring seated in the groove.

7. Beater mechanism according to claim 3, wherein the engaged bearing portions of the shaft and socket are axially relatively short as compared to the overall axial length of the shaft and socket.
